The ornamental design for a hot air distributor for dishwasher as shown and described.

DESCRIPTION

FIG. 1 is a front perspective view of a hot air distributor for dishwasher showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded perspective view of the claimed design; and,

FIG. 9 is a perspective view showing the design in state of use that the claimed design has been placed at the bottom part of the dishwasher.

The broken lines depict portions of the hot air distributor for dishwasher that form no part of the claimed design. The portions of FIG. 9 drawn in broken lines show environmental structure only and form no part of the claimed design.
